UNITED STATES PATENT OFFICE.

MAX LEITNER, OF CHICAGO, ILLINOIS.

SANITARY NIGHT-STOOL.

1,199,391.

Specification of Letters Patent. Patented Sept. 26, 1916.

Application filed December 6, 1915. Serial No. 65,217.

To all whom it may concern:

Be it known that I, MAX LEITNER, a citizen of the United States of America, and a resident of Chicago, in the county of 5 Cook, State of Illinois, have invented certain new and useful Improvements in Sanitary Night-Stools, of which the following is a specification.

This invention relates to improvement in 10 portable night stools or seats for household or like uses, and has for its object to provide a simple and substantial structural formation and association of parts in a night stool or seat, adapted for convenient and 15 comfortable occupancy, and with which the excrements are directed into a readily removable pail or receptacle in a certain and effective manner, and in which a leakage of foul gases from the apparatus, when not 20 in actual use, is effectively prevented all as will hereinafter more fully appear.

In the accompanying drawings:—Figure 1, is a central vertical section of an apparatus embodying the structure of the present 25 invention. Fig. 2, is a fragmentary plan view, the top or cover being omitted.

Similar reference numerals indicate like parts in both views.

Referring to the drawing, 1 designates 30 the upper part of an open-top casing providing a pail or bucket receptacle, formed with an upwardly flaring side wall, with an expanded bottom portion or supporting base 2 having a beaded lower edge, and 35 with an open beaded top which in the present structure is associated with an outer annular wall 3, arranged in spaced relation to the annular side wall of the casing 1, and forming in connection with 40 said side wall and a converging bottom web 4 an annular open top chamber adapted to contain a sealing body of water or the like, and into which the marginal downturned rim 5 of the top cover 6 of the apparatus, 45 dips, to form a gas tight closure for the interior of the main casing 1. The annular outer wall 3 extends a distance above the top margin of the aforesaid side wall of the casing 1 so that the usual orificed seat 50 7 may rest upon the top of said side wall

and be inclosed by the outer wall 3 and top cover 6 associated therewith. Beneath the converging bottom web 4 are depending flanges forming handles whereby the stool can be lifted and carried from place to 55 place. The bottom of the upper part of the open top casing and the upper part of the expanded bottom portion or supporting base 2 are seamed together.

8 designates an ordinary handled pail or 60 bucket adapted to occupy the interior of the casing 1 and rest upon the bottom web of the same in a removable manner. Said pail is adapted to receive the excrements voided by the person using the apparatus. 65

9 designates an annular rim having a flange whereby it is secured to the underside of the orificed seat 6 aforesaid, and adapted to fit the open top of the pail or bucket 8 to properly position the parts as 70 well as to direct the excrements in a certain manner into the pail or bucket 8 aforesaid.

Having thus fully described my said invention what I claim as new and desire to 75 secure by Letters Patent, is:—

A portable night-stool comprising a casing having an upper part providing a pail or bucket receptacle, formed with an upwardly-flaring side wall having a beaded 80 upper edge, with a downwardly-expanded supporting base, having a beaded lower edge, the upper part and the base being seamed together, and with an exterior annular side-wall having a beaded top and 85 providing a water chamber and extending a distance above the upper part and having a converging bottom web and depending flanges beneath the bottom web providing lifting handles, a cover seating on the 90 beaded top of the side wall and having a marginal downturned rim dipping into the water chamber, and an orificed seat, resting upon the beaded top of the upper part of the casing and having a depending 95 flanged annular rim spaced from the upper part of the casing.

Signed at Chicago, Illinois, this 3rd day of December, 1915.

MAX LEITNER.
